[57] CLAIM

The ornamental design for the cosmetic powder compact, as shown and described.

DESCRIPTION

FIG. 1 is a front view of a compact showing our new design the side opposite being identical;

FIG. 2 is a top view thereof;

FIG. 3 is a bottom view thereof;

FIG. 4 is a side elevational view of the base of the compact, shown separately for clarity of illustration; the side opposite being identical except for the position of the catch elements;

FIG. 5 is a bottom plan view of the cover, shown separately for clarity of illustration; and,

FIG. 6 is a top plan view of FIG. 4.

FIG. 1FIG. 2*FIG. 3*FIG. 4*FIG. 5*FIG. 6
